UNITED STATES PATENT OFFICE.

WILLIAM E. BLATTAU, OF CHICAGO, ILLINOIS.

BOTTLE-CLOSURE.

1,196,510.

Specification of Letters Patent. Patented Aug. 29, 1916.

Application filed September 13, 1915. Serial No. 50,387.

To all whom it may concern:

Be it known that I, WILLIAM E. BLATTAU, a citizen of the United States, residing at Chicago, in the county of Cook and State 5 of Illinois, have invented certain new and useful Improvements in Bottle-Closures, of which the following is a specification.

My invention relates to bottle closures.

One of the objects of my invention is to 10 provide a simple, one piece, efficient and sanitary receptacle closure.

Another object of my invention is to provide a jar or bottle closure that effectively covers the boundary wall of the mouth of 15 the jar or bottle and which will retain itself in place and can be quickly removed and replaced.

Other and further objects of my invention will become readily apparent, to persons skilled in the art, from a consideration 20 of the following description when taken in conjunction with the drawings wherein:—

Figure 1 is an elevation of a milk bottle showing my closure in place thereon. Fig. 2 is a central section through the closure and a fragment of the bottle. Fig. 3 is a plan view of the sheet of metal blank of which the closure is made before the side wings are bent into place.

50 In all the views the same reference characters are employed to indicate similar parts.

My improved closure is especially well adapted for use for temporarily closing jars or bottles, such as milk bottles and the like. 55 The ease with which it may be applied to and removed from such receptacles, its low manufacturing cost and its simplicity of operation render it very desirable.

The device is preferably made from sheet 60 metal, of a springy or resilient character, blanked out as shown in Fig. 3. The main body part 5 is generally circular in outline and is provided with oppositely extending wings 6 and 7, the terminal outer edges of 65 which are concave or inwardly curved, as at 8, and somewhat rounded at the corners, as at 9, the wings are each downturned, as at 10, and inturned, as at 11, so that the confronting curved edges 8—8, where they contact the neck of the bottle, are somewhat 70 closer together than the distance corresponding with the diameter of the neck 12 of the bottle 13. From the body part 5 is upwardly deflected an annular bead 14 which is of substantially the same diameter and 75 dimension as the mouth 15 of the bottle, so

that the wall of the mouth of the bottle is effectively covered thereby to prevent contaminating agencies from contact with it, such as flies or the like, when the cover is 80 in place.

To apply the closure it is only necessary to place the rounded edges 9 in position with respect to the neck of the bottle, and gently push it into place, when the side wings 6 85 and 7 will be moved outwardly and by the resiliency of the metal of which they are composed will be returned to contact with the bottle, the curved edges 8 serving to yieldingly hold the closure in place and the 90 bead 14 will settle down over the mouth 15 of the bottle. When lateral pressure is applied to either side of the closure, as on the wings 6 or 7 to remove the closure from the bottle the wings, as a result of the curved 95 portion 8 and the projecting edges 9 are outwardly deflected and when the projections 9 pass beyond the immediate diameter of the neck of the bottle, in the operation of removing the closure, the curvature of the 100 neck of the bottle will facilitate removal of the closure.

The device is very easily put in place and removed and serves as a temporary means for closing the bottle to prevent entrance of 105 insects or other objectionable matter into the interior of the bottle and is intended to take the place of the less convenient usual paper cover.

While I have herein shown a single embodiment of my invention, for the purpose of clear disclosure, it is evident that changes may be made in the general form and configuration of the device within the spirit and scope of the appended claims.

Having described my invention, what I claim is:—

1. A receptacle closure comprising a generally round, thin body part and attachment means arranged for sidewise removal 100 or attachment to a receptacle neck, said attachment means comprising laterally projecting integral wings having inwardly curved end portions, the wings extending outwardly beyond the periphery of the receptacle neck in the same plane as the body part, then downwardly and inwardly, the end edges of the wings being concaved on a radius substantially equal to that of the receptacle neck to make contact therewith and 105 impositively lock the closure in place.

2. A closure cap for the mouth of a milk

bottle or similar large mouthed receptacle having a peripheral bead; comprising a round, thin, generally flat body part adapted to seat upon the end of the bottle mouth; and attachment wings integral with the cap and arranged for sidewise removal or attachment to the receptacle neck, said attachment wings extending laterally from the cap at diametrically opposite points and projecting beyond the periphery of the bottle neck in the same plane as the body part of the cap, the end portions thereof being

formed downwardly and inwardly with their end edges arcuately formed about the axis of the bottle as a center to make resili-
15 ent contact with the neck of the bottle and impositively lock the closure cap in place.

In testimony whereof I hereunto set my hand in the presence of two subscribing witnesses.

WILLIAM E. BLATTAU.

In the presence of—

STANLEY W. COOK,
MARY F. ALLEN.
